United States Patent Office.

THOMAS JENKYN, OF THETFORD CENTRE, ASSIGNOR TO BARTLETT BURR,
OF FAIRLEE, VERMONT.

Letters Patent No. 77,195, dated April 28, 1868.

IMPROVEMENT IN SAWING-MACHINES.

The Schedule referred to in these Letters Patent and making part of the same.

TO ALL WHOM IT MAY CONCERN:

Be it known that I, THOMAS JENKYN, of Thetford Centre, in the county of Orange, and State of Vermont, have invented a new and improved Sawing-Machine; and I do hereby declare that the following is a full, clear, and exact description thereof, which will enable those skilled in the art to make and use the same, reference being had to the accompanying drawings, forming part of this specification.

This invention consists in a novel arrangement of circular saws and rotary cutters in connection with frames and tables, as hereinafter fully shown and described, whereby a machine is obtained which is capable of performing various kinds of work, such as slitting boards, planks, or other stuff, cross-cut sawing, the cutting of shoulders or tenons, grooving or beading, and chamfering or cornering. In the accompanying drawings—

Figure 1, Sheet No. 1, is a vertical section of my invention, taken in the line xx' , fig. 2.

Figure 2, a plan or top view of the same, with the slitting-table raised.

Figure 3, a detached end view of a table pertaining to the same.

Figure 4, Sheet No. 2, a vertical section of the invention, taken in the line yy' , fig. 5.

Figure 5, a plan or top view of the same, with the slitting-table down in a working position.

Figure 6, Sheet No. 3, a vertical section of the same, taken in the line zz' ; fig. 9.

Figure 7, a vertical section of the same, taken in the line $z'z'$, fig. 8.

Figure 8, a plan or top view of a portion of the machine, with the chamfering and cornering-bed attached.

Figure 9, a plan or top view of a portion of the same, with the grooving and beading-table attached.

Figure 10, a section of the beading-cutter head, taken in the line $x'x'$, fig. 6.

Figure 11, a section of the chamfering and cornering-cutter head, taken in the line $y'y'$, fig. 7.

Similar letters of reference indicate corresponding parts.

The framing of the machine is composed of two distinct parts, A B, connected together so as to form one structure. On the framing A there are placed two horizontal saw-arbors, C D, on which circular saws E F are placed, the saw-arbors being driven by belts $a a'$ from a driving-shaft, G, in the lower part of the portion A of the framing of the machine.

On the upper part of the portion A of the framing there is secured, by hinges b , a table, H, having a slot, c, made in it for the saw E to work through, and having upon it a gauge, I, and a bed, J, the latter being provided with a longitudinal central bead or rail, d. On this bed J a slide, K, is placed, the latter having a longitudinal groove, e, made in its under side, to receive the bead or rail d of the bed J. This slide K is provided at one end with a stop, f, against which one end of the board, plank, or other stuff to be operated upon is placed. This slide K and the saw E are used for slitting, a proper width of cut being obtained by adjusting the gauge I. This will be fully understood by referring to fig. 5.

On the upper part of the portion B of the framing there are placed two parallel ways, L L, which are secured to the fixed bars $g g$ on B, by means of screws passing through vertical slots in the ways and into the bars g . These ways are allowed to rise and fall freely, and they rest upon inclined surfaces $h h$ on bars M, which are placed transversely in the portion B of the framing, and connected by longitudinal bars N N, through one of which a screw, O, passes, by turning which the bars M may be moved, and the ways L L adjusted higher or lower, as may be required. On these ways L L, a cutting-off or cross-cut table, P, is placed, which is used with the saw F; and it is for the purpose of raising and lowering the table P that the ways L L are made adjustable, a variation in the thickness of the stuff rendering this necessary, and the adjustment of the table also admitting of the saw F being used for cutting shoulders and tenons on the stuff.

Q represents a table used for slitting and halving work together. This table has two pendent strips, R R', attached to it by hinges, i i. The strip R has two slots, j j, made longitudinally or vertically in it, and the other strip, R', has one slot, k, made in it. In using this table Q, the hinged table H is raised, (see figs. 1 and 2,)

and the table Q applied to the part A of the framing by slipping the strips R R' over horizontal screws l l m in the part A, the screw m serving as a set-screw. This table Q is provided with an adjustable gauge, S.

T represents a table, which has a convex upper surface, and is secured, when in use, to the hinged table H. This table T has a Y-shaped groove, n, made longitudinally in it; and a slot, o, is made entirely through the table, to allow the upper part of a cutter-head, U, to work in, said cutter-head being placed in the arbor of the saw F. This table T and cutter-head U are used for chamfering or cornering work.

V is a table, which is used for beading and grooving-work. This table is attached to the hinged table H in the place of bed J, the latter being detached. The table V has a slot, p, made in it, to receive a cutter-head, W, provided with grooving or beading-cutters, p^x, the cutter-head W being placed on the arbor of saw F.

This machine is extremely simple in construction, and may be constructed at a very small cost beyond that of an ordinary circular-saw machine. The various kinds of work that may be performed by it renders it extremely valuable in the shop of a joiner or worker in wood.

Having thus described my invention, what I claim as new, and desire to secure by Letters Patent, is—

The construction and arrangement of the reciprocating table P, hinged table H, tables Q T V, saw-arbors C D, and cutter-heads U W, all operating upon the same frame, in the manner and for the purposes herein shown and described.

THOMAS JENKYN.
